UNITED STATES PATENT OFFICE.

JAMES SHORTT, OF LOS ANGELES, CALIFORNIA, ASSIGNOR TO ALLOY METAL PRODUCTS CO., OF LOS ANGELES, CALIFORNIA, A COPARTNERSHIP COMPOSED OF JAMES SHORTT AND CLAUDE E. CHAPMAN.

DESIGN FOR A LANTERN ELECTRIC-LIGHT FIXTURE.

Application filed May 9, 1928. Serial No. 26,613. Term of patent 3½ years

To all whom it may concern:

Be it known that I, JAMES SHORTT, a citizen of the United States, residing at Los Angeles, in the county of Los Angeles and State of California, have invented a new, original, and ornamental Design for a Lantern Electric-Light Fixture, of which the following is a specification, reference being had to the accompanying drawing, forming part thereof.

Fig. 1 is a side elevation of my design.
Fig. 2 is a front elevation of my design.
Fig. 3 is a top plan view of my design.

I claim:

The ornamental design for a lantern electric-light fixture, as shown.

JAMES SHORTT.
